UNITED STATES PATENT OFFICE.

ARTHUR KITSON, OF PHILADELPHIA, PENNSYLVANIA, ASSIGNOR TO THE KITSON HYDROCARBON HEATING AND INCANDESCENT LIGHTING COMPANY, OF SAME PLACE AND CHARLESTON, WEST VIRGINIA.

THERMOSTATIC VALVE AND VAPOR-TUBE.

SPECIFICATION forming part of Letters Patent No. 665,111, dated January 1, 1901.

Application filed February 16, 1900. Serial No. 5,306. (No model.)

To all whom it may concern:

Be it known that I, ARTHUR KITSON, a subject of the Queen of Great Britain, and a resident of Philadelphia, (Germantown,) county 5 of Philadelphia, State of Pennsylvania, have invented certain new and useful Improvements in Thermostatic Valves and Vapor-Tubes, of which the following is a specification.

10 My invention relates generally to vapor-burning apparatus; and more specifically it consists of an automatic valve constructed and located to be operated thermostatically in admitting, regulating, and cutting off the 15 supply of oil to the vaporizing-chamber of the apparatus.

In the various forms of apparatus burning the vapor of a fluid hydrocarbon supplied under pressure considerable difficulty has 20 been experienced in thermostatically regulating the admission, supply, and cut off of oil to the vaporizing-chamber. Such difficulty arises mainly from failure to maintain the inlet closed until the temperature of the 25 chamber has been raised to the vaporizing-point, which results in flooding the chamber, clogging the vapor-outlet, or discharging the oil upon the furniture or contents of the room in which the lamp is being operated, &c.

30 It is the object of my invention, therefore, to obviate the objections above set forth through the employment of a valve, self-closing, to normally cut off all flow of oil—i. e., under atmospheric temperature—and 35 which opens to admit oil to the vaporizing-chamber only when the temperature of the same has been raised to the point of vaporization or nearly to said point.

The preferred form of apparatus embodying my invention is illustrated by a view 40 in sectional elevation in the accompanying drawing.

The vaporizing tube or chamber 1 is connected to the oil-supply pipe 3 by means of 45 a threaded union 2 in the well-known way. The pipe 3, leading from the source of oil-supply, is controlled by any suitable form of valve 4 which is capable of accurate adjustment to prevent the discharge of oil under

pressure or to permit the flow of the same in 50 requisite quantities. The end of the vaporizing-tube at which the oil is admitted is preferably made in the form of a casting 5, having a valve-chamber 6 and a valve-seat formed therein for the cone-valve 7; also, a 55 central bore extending throughout its length of a diameter slightly in excess of the valve-stem 8, so that when the valve is open the oil will be admitted to the tube in the form of a thin film. A spring 9, bearing against 60 the inner face of a screw-cap 5^a, which closes the open end of the casting, encircles that portion of the valve-stem lying within the chamber 6, and serves to maintain the valve 65 normally closed.

Within the body of the vaporizing-tube, and preferably concentric with the axis thereof, a thermostat rod or filler 10 is mounted by being threaded at one end in a screw-plug 11, which latter is tapped into and closes the 70 end of the tube 1, and at the opposite end the rod 10 is loosely entered in the bore of the casting 5 and is thereby aligned with the contained valve-stem, there being a space or clearance between the adjoining ends of the 75 rod and stem which may be varied at will for a purpose to be later on described. A jam or lock nut 12 on the threaded end of the rod serves to secure the latter in any position to which it may be adjusted. The plug 11 is 80 shouldered to abut against the end of the tube, at which point its diameter is enlarged to equal the same, and it is threaded throughout its larger diameter for engagement with a cap 13. This cap incloses the outer projecting end of the thermostat and is socketed at 14 to allow for movement of the latter under adjustment.

15 represents the vapor-discharge opening in the lower side of the tube, and 16 the upper end of the mixing-tube, which is here shown in dotted lines relatively arranged to receive the jet of vapor, as indicated.

17 17 represent gauzes which may be inserted in the vaporizing-tube and arranged 90 concentrically about to aid in centering the thermostat-rod, as shown.

The outer wall of the casing of the vapor-

burning apparatus is indicated by the dotted lines 18 18, and with the tube relatively arranged as shown the main portion of the thermostat will lie within the casing in position to be surrounded by the hot gases, &c., in their escape from the burner to the chimney.

It will be observed that the ends of the tube are accessible, in that they lie outside of the casing in an exposed position, and under the cooling action of the air at atmospheric temperature both the spring-seated valve and the fixed end of the thermostat will be more or less protected from the heat generated by the burner. This arrangement also serves to greatly facilitate adjustment or examination of either the valve or thermostat, in that it does not necessitate the removal of the tube from the casing.

The mode of operation of my invention is as follows: With the vaporizing-tube in operative relation to the lamp or other vapor-burning apparatus the thermostat-rod is adjusted and secured by the lock-nut to provide a space between its free end and the adjoining end of the valve-stem. To effect the opening of the valve, it is necessary that the thermostat-rod shall expand at a greater rate of speed than the tube, and at the same time it is also essential that the valve should remain closed until the temperature of the vaporizing-chamber has been raised sufficiently to effect vaporization of the oil when admitted. I secure the required difference in the rate of expansion by constructing the vaporizing-tube of steel or an equivalent metal and the thermostat-rod of brass, and regulate or retard the opening of the inlet-valve by varying the space or clearance between the valve-stem and the end of the thermostat. Normally, however, the valve is maintained closed by its spring, and all access of oil to the vaporizing-chamber is thereby prevented. When the preheating of the vaporizing-tube is brought about in any one of the well-known ways—*i. e.*, by the flame of a torch or Bunsen burner—for the purpose of starting the lamp into operation, the rod 10 will expand faster than the tube 1, as above set forth, and in being secured at one end will advance under expansion in the direction of the valve-stem. During the interval in which the rod is being lengthened by expansion to engage and operate the valve the temperature of the vaporizing-chamber will be brought up to the point required to effect the vaporization of the oil, and when the valve is finally moved from its seat in opposition to the spring the oil under pressure passes into the vaporizing-chamber in the form of a film, where it is converted into vapor and issues from the orifice 15 in the form of a jet. The vapor thus formed is burned in the vapor-burner in the well-known way, and the heat generated maintains the tube 1 at the necessary temperature for continued vaporization of the oil therein. As

long as this temperature is maintained the valve will remain open. If, however, the lamp goes out for any reason whatever, the thermostat will cool down rapidly, and in contracting with greater rapidity than the tube will move away from the valve-stem and allow the spring to act and close the valve, thereby preventing further admission of oil to the chamber.

Some of the main advantages of my invention lie in the saving of oil by preventing waste thereof by defective valve mechanism; further, in preventing flooding of the vaporizing-chamber and escape of oil by effecting a slow or retarded opening and a quick closing of the inlet-valve; further, in the adaptability of the valve mechanism to vapor-tubes now in general use, and, finally, in the convenience and facility with which the valve mechanism may be adjusted, examined, or repaired without removing the tube from the casing of the apparatus.

It is evident, of course, that various changes could be made in the details of construction illustrated without departing from the spirit and scope of my invention so long as the principle of operation described in the specification or the general relative arrangement of parts illustrated in the drawing is preserved. Other forms of thermostat might be employed and different forms of valve might be substituted. The thermostat might be differently located so long as it is within the heating zone of the lamp-burner and of the preheating device.

Having therefore described my invention, what I claim as new, and desire to protect by Letters Patent, is—

1. The combination with a vapor-burning apparatus, of a vaporizing-chamber provided with requisite inlets and outlets, a valve closing the inlet and a thermostat controlling the valve, and lying normally separated therefrom a definite distance whereby the valve will open at a predetermined temperature.
2. The combination with a vapor-burning apparatus, of a vaporizing-chamber provided with requisite inlets and outlets, a valve closing the inlet, and a thermostat controlling the valve and lying normally separated therefrom, said thermostat being adjustable to vary the distance of separation from the valve.
3. The combination with a vapor-burning apparatus, of a vaporizing-chamber provided with requisite inlets and outlets, a self-seating valve closing the inlet, and a thermostat controlling the valve and lying normally separated therefrom, said thermostat being adjustable to vary the distance of separation from the valve.
4. The combination with a vapor-burning apparatus of a vaporizing-chamber provided with requisite inlets and outlets, a spring-seated valve closing the inlet, and a thermostat controlling the valve and lying normally separated therefrom, said thermostat

- being adjustable to vary the distance of separation from the valve.
5. The combination with a vapor-burning apparatus, of a vaporizing-chamber provided with requisite inlets and outlets, a self-seating valve closing the inlet, and a thermostat controlling the valve and lying normally separated therefrom, said thermostat and vaporizing-chamber being movable under expansion or contraction at different rates of speed. 65
6. The combination with a vapor-burning apparatus, of a vaporizing-chamber provided with requisite inlets and outlets, a self-seating valve closing the inlet, and a thermostat controlling the valve and lying normally separated therefrom, said thermostat and vaporizing-chamber being movable in the same direction under expansion or contraction at different rates of speed. 70
- 20 7. The combination with a vapor-burning apparatus, of a vaporizing-chamber provided with requisite inlets and outlets, a self-seating valve closing the inlet, and a thermostat controlling the valve, and lying normally separated therefrom, said thermostat and vaporizing-chamber being movable in the same direction under expansion or contraction, the thermostat moving at a greater speed to effect an engagement with the valve. 75
- 25 8. The combination with a vapor-burning apparatus, of a vaporizing-chamber provided with requisite inlets and outlets, a self-seating valve closing the inlet, a thermostat controlling the valve and lying normally separated therefrom, said thermostat and vaporizing-chamber being movable in the same direction under expansion or contraction, the thermostat moving at a greater speed and being adjustable to vary the normal distance of 80 separation from the valve. 90
- 30 9. The combination with a vapor-burning apparatus, of a vaporizing-chamber provided with requisite inlets and outlets, a valve-chamber exterior to the vaporizing-chamber, a valve and its seat in the valve-chamber, said valve controlling the oil-inlet and a thermostat in operative relation to the valve and normally separated therefrom. 95
- 35 10. The combination with a vapor-burning apparatus and its casing, of a vaporizing-chamber provided with requisite inlets and outlets, a valve-chamber located exterior to the casing of the vapor-burning apparatus, a valve in the chamber controlling the oil-inlet, and a thermostat in operative relation to the valve and normally separated therefrom. 100
- 40 11. The combination with a vapor-burning apparatus and its casing, of a vaporizing-chamber provided with requisite inlets and outlets, a valve-chamber located exterior to the casing of the vapor-burning apparatus and provided with a removable cap, a valve in the chamber controlling the oil-inlet and a thermostat in operative relation to the valve and normally separated therefrom. 105
- 45 12. The combination with a vapor-burning apparatus, of a vaporizing-chamber provided with requisite inlets and outlets, a valve controlling the inlet, and a thermostat within the vaporizing-chamber having one end fixed and its free end lying in operative relation to but separated from the valve a definite distance whereby the valve will open at a predetermined temperature. 110
- 50 13. The combination with a vapor-burning apparatus, of a vaporizing-chamber provided with requisite inlets and outlets, a valve controlling the inlet, a thermostat within the vaporizing-chamber having one end fixed and its free end lying in operative relation to but separated from the valve, and means exterior to the vaporizing-chamber for adjusting the thermostat to vary the distance of separation from the valve. 115
- 55 14. The combination with a vapor-burning apparatus and its casing, of a vaporizing-chamber provided with requisite inlets and outlets, a valve controlling the inlet, a thermostat within the vaporizing-chamber having one end fixed and its free end lying in operative relation to but separated from the valve, and means exterior to the vaporizing-chamber and casing of the vapor-burning apparatus for adjusting the thermostat to vary the distance of separation from the valve. 120
- 60 15. The combination with a vapor-burning apparatus, of a vaporizing-chamber provided with requisite inlets and outlets, a valve controlling the inlet, a thermostat within the vaporizing-chamber having one end fixed and its free end lying in operative relation to but separated from the valve, means exterior to the vaporizing-chamber for adjusting the thermostat, and a detachable cap inclosing the adjusting device. 125
- 65 16. The combination with a vaporizing apparatus, of a vaporizing-tube provided centrally with a vaporizing-chamber having requisite inlets and outlets, a valve and its chamber at one end of the tube, said valve controlling the inlet, a thermostat within the vaporizing-chamber in operative relation to the valve, a thermostat adjusting device and its chamber at the opposite end of the tube and removable caps serving as inclosing casings for the terminal chambers. 130
